UNITED STATES PATENT OFFICE.

CARL F. SCHULZ, OF BROOKLYN, NEW YORK.

CARBURETOR.

Application filed December 22, 1916. Serial No. 138,322.

To all whom it may concern:

Be it known that I, CARL F. SCHULZ, a citizen of the United States of America, residing in the borough of Brooklyn, county 5 of Kings, city and State of New York, have invented certain new and useful Improvements in Carburetors, of which the following is a specification.

This invention relates to automatic in- 10 take-air temperature-adjusting devices for internal combustion engines. The invention is more particularly designed for use in an apparatus which supplies heated air and atmospheric air for mixture with the fuel de- 15 livered from the carburetor, one of the objects of the invention being to thermostatically control the opening of the air valves, the hot air valve being opened more and more as the temperature of the incoming 20 air supply rises, and upon the hot air valve being opened to a predetermined amount, preferably fully opened, the cold air valve being then opened, the amount of opening of such cold air valve being thermostatically 25 regulated in accordance with the resultant temperature of the combined currents of cold and hot air. By means of this invention the ranges of temperature of the air admitted is automatically regulated, and the 30 volume of such air is proportioned to its temperature. A low temperature limit for the air is fixed, below which temperature the valves are held in their closed positions and are opened only when and as they can de- 35 liver air at the desired temperatures, thus keeping the temperature uniform.

Upon starting cold with my improved carburetor, no change in adjustment need be made. For the reason that both hot and 40 cold air intakes are in closed positions, in this way a very rich mixture is fed to the engine because of the great vacuum created in the carburetor, a vacuum sufficient to start even when the motor is entirely cold. The 45 hot air valve is constructed to open very quickly upon a slight rise in temperature and to be entirely opened to admit full warm air almost at once. It is regarded as good practice in starting to open the throttle about one-third. According to my present 50 improvement the throttle valve is so con-

nected with the hot air valve that the movements of the hot air valve at starting are not interfered with upon the normal or customary throttle opening, when, however, occasion demands, as for instance, to continue the running of the motor after starting and before sufficient heat is generated to cause the thermostat to operate, the operator by opening the throttle beyond the amount for 60 which the instrument is adjusted, the hot air valve is opened irrespective of temperature conditions. Also, during running, if the operator opens the throttle beyond a predetermined amount, the hot air valve is 65 caused, should it not be thermostatically proportionately opened, to open in proportion to the throttle opening.

To prevent an excess of hot air, the illustrated construction provides for a movement 70 of the hot air valve beyond the point of maximum opening, so that it begins to close the passage again when the point of maximum opening has been reached. Meanwhile the cold air valve opens wider and wider up 75 to the stop provided at the position of maximum opening.

In the drawings accompanying and forming a part of this specification, one practicable embodiment of the invention is illus- 80 trated, in which drawings,

Fig. 1 is a view, partly in elevation and partly in central section, of the device, this view being taken looking at the structure from the throttle valve or engine connection 85 side;

Fig. 2 is a similar view at substantially right angles to the position illustrated in Fig. 1;

Fig. 3 is a broken-away view similar to 90 Fig. 1, Fig. 1 showing the valves closed and Fig. 3 showing them fully open, and

Fig. 4 is a detail.

In the illustrative example shown in the drawings, within the casing 1 there is assumed to be some suitable carburetor float chamber and mixing chamber communicating by means of a passage through the coupling 3 with the manifold or other connection for the internal combustion engine. 95 There is also provided an inlet 4 for hot air and an inlet 5 for cold air. In the present 100

illustration, the hot air inlet 4 is shown at the upper part of the device, and the cold air inlet just below this and arranged at substantially right angles thereto and above the outlet at 3, this having been found in practice to be a convenient arrangement of the parts.

Between the engine connection 3 and the casing 1 there is shown a short conduit 6, 10 within which is mounted the throttle valve 7, such valve being shown fast upon a shaft 8, to which shaft there is shown attached an operating lever 9, which is adapted to be actuated in some suitable manner, a broken-away connection being shown at 10, which will be attached to some suitable operating device. A stop 11, in the form of a lug on the casting, is shown for limiting the movement of the throttle. An adjustable stop 12 15 is shown for limiting the opening movement of the throttle, the closing movement being limited by the engagement of the arm 2 with the lug.

The passage of hot air into the port or 25 inlet 4 is controlled in the present illustration by means of a butterfly valve 13, shown mounted fast upon a shaft 14, such shaft being mounted in suitable bearings in the framework. The shaft is shown extending 30 at one end, and there provided with a coiled spring 15 (see Fig. 4) for normally holding the valve in a closed position. It is preferable to maintain the valve slightly open, so that at starting a small amount of air is 35 drawn in through the port 4 in any event, irrespective of the action of the thermostat or other devices. A back-stop 16 is provided for this purpose, such back-stop in the present instance being in the form of a set-screw and lock nut. When the set-screw is 40 turned in slightly, as, for instance, in the manner illustrated in the drawings, a certain amount of clearance is given around the valve 13, which amount of clearance can be 45 adjusted from time to time as occasion may demand.

The passage of cold air into the port or 50 passage 5 is controlled by means of a butterfly valve 17 shown mounted fast upon a shaft or spindle 18 suitably mounted in the framework, which shaft is shown projecting at one end and there provided with a coiled spring 19 adapted to normally hold the valve in its closed position against the backstop 20. 55 This back-stop is shown in the form of a set-screw.

A lost motion toggle connection is provided between the hot air valve 13 and the cold air valve 17 by means of a pair of links 60 21, 22 and a crank 23. The link 21 is shown mounted upon the shaft 14 and fast with the valve 13, a suitable set-screw 24 being provided for adjusting the position of these parts thereon. The link 21 is shown articulated to the link 22, which latter link has a

slot 25 engaging a wrist pin 26 carried by the crank 23. The crank 23 is fast with the valve 17, a set-screw 27 being provided for effecting the angular adjustment of these parts upon the shaft 18.

A thermostat is illustrated located in the delivery chamber between the point of confluence of the hot and the cold air currents and the engine connection 3. The form of this thermostat is not a part of this invention, but, for the purpose of understanding its relations to the apparatus herein illustrated, it may be pointed out that it in a general way comprises a casing 28 mounted on suitable supports within the general casing or framework of the apparatus. Within the casing 28 there is a member 29 adapted to expand and contract upon the rising and falling of the temperature of its surrounding medium. This member 29 acts upon a longitudinal reciprocable plunger 30 which has a lost motion connection with the toggle connection between the valves 13 and 17. To be more specific, a link 31 is shown articulated to the upper end of the plunger 30, and its upper end provided with a slot 32 engaging a pin 33 on the link 21.

The actuator for the throttle valve is shown provided with a lost motion connection with the hot air valve 13, such connection being in the form of a link 34 articulated to an arm 35 carried by the shaft 14, the lower end of which link 34 has a pin 37 disposed in a slot 36 in the throttle valve arm 9.

The operation of the form of the device herein illustrated is substantially as follows: As was above stated, it is to be assumed that the chamber 1 is in communication with a source of fuel supply, as, for instance, a carburetor and a source of utilization, as, for instance, an internal combustion engine. The operator opens the throttle valve by raising the connection 10, which opens the device to the suction of the engine, whereupon air is drawn in through the hot air port 4 past the valve 13, which is held slightly from its seat by means of the adjustable abutment 16. The range of movement of the throttle valve in its normal actuation is such that the lost motion afforded between the link 34 and the throttle valve-actuator arm 9 by means of the pin and slot connection 37, 36, is such that the automatic actuation of the valve 13 is not interfered with.

The in-rushing hot air through the port 4 acts upon the thermostat and causes the plunger 30 to rise. The positions of the parts at starting are shown in Fig. 1. As the thermostatic plunger 30 is pressed upwardly, it in turn presses upwardly the link 31, the lower end of the slot 32 of which is at this time in engagement with the pin 33. This movement acts upon the toggle connection between the valves 13 and 17, but, in

the initial stages only in a manner operative upon the valve 13, the parts being so relatively located and timed that the valve 13 is about fully opened by means of the thermostat 5 acting in response to the temperature of the incoming heated air before the cold air valve 17 is moved from its seat at all. When the parts are located in the relative positions shown in the drawings, the 10 valve 13 can assume a vertical position before the valve 17 is acted upon. As the air in the chamber surrounding the thermostat becomes more heated, incident to the rise in temperature of the air admitted through the 15 port 4, the toggle links 21 and 22 are moved further and the lost motion allowed by means of the slot 25 and pin 26 is exhausted, whereupon the end of the slot engages the pin and swings the shaft 18 upon its axis 20 against its spring 19 and moves the cold air valve either slowly or rapidly from its closed position, as the case may be, thereby admitting cold air which mingles with the hot air, and the current of the mingled 25 air passes the thermostat, which, in a short time, assumes and causes the respective valves to assume a position of substantial equilibrium, maintaining the proper temperature of inflowing current of air. Fig. 3 30 shows the cold air valve fully open. The movement of the actuating parts in opening the cold air valve 17, in the present embodiment of the invention, partly closes the valve 13. The movement of the valve from 35 its vertical position to its Fig. 3 position retards the volume of hot air being admitted, having a choking action, so that it might properly be said that the volume of hot air is proportionally diminished with 40 the opening of the cold air valve.

At times the operator may desire to open up fully the hot air valve, irrespective of the action of the thermostat upon it. In this case the throttle is opened beyond its normal range of opening, which exhausts the 45 lost motion permitted between the throttle valve arm 9 and the link 34, whereupon the valve 13 is opened more or less and may be opened to the full extent of its opening 50 movement. It will thus be seen that the throttle valve-actuator can be employed for opening the throttle and the hot air inlet, but that it only opens the latter upon excess movement, and should preferably be so adjusted that under no circumstances can it 55 open the cold air inlet.

Although but one illustrative example of an embodiment of the invention is shown and described in detail, it will be apparent 60 that various changes may be made as occasion demands, within the scope of the claims, without departing from the spirit of the invention.

Claims:

65 1. In an apparatus of the character de-

scribed, the combination with a chamber having a hot air inlet and a cold air inlet, and valves for the respective inlets, of a thermostat associated with said chamber, a lost motion toggle connection between said hot air valve and the cold air valve, and a connection between the thermostat and said toggle connection, the connections being timed for opening the hot air valve more or less incident to increase or decrease in the 70 temperature of the air passing said valve and for opening the cold air valve when the hot air valve has assumed a predetermined position, and the air passing through the same has acquired a predetermined temperature, and opening such cold air valve more or less incident to increase or decrease in the 75 temperature of the combined currents of air passing both of said valves, and manually operable means arranged exteriorly of 80 said chamber for similarly actuating said valves independently of said thermostatic means.

2. In a device of the character described, the combination with a chamber having a 90 hot air inlet and a cold air inlet, valves for the respective inlets, means for urging the valve in said hot air inlet towards its seat, an adjustable stop for preventing the seating of such valve, of a thermostat associated 95 with said chamber; a lost motion toggle connection between the said hot air valve and the cold air valve, and a connection between the thermostat and the said toggle connection, the connections being timed for opening the hot air valve more or less incident to increase or decrease in the temperature of the air passing such valve, and for opening the cold air valve upon the coincidence 100 of a predetermined amount of opening of the hot air valve and a predetermined rise of temperature of the air passing the same, and opening such cold air valve more or less incident to increase or decrease in the temperature of the combined currents of air 110 passing both the said valves.

3. In a device of the character described, the combination with a chamber having a hot air inlet, a cold air inlet and an outlet, valves for the respective inlets and a 115 valve for the outlet, of a thermostat associated with said chamber, a lost motion toggle connection between the said hot air valve and the cold air valve, and a connection between the thermostat and the said toggle 120 connection, the connections being timed for opening the hot air valve more or less incident to increase or decrease in the temperature of the air passing such valve and for opening the cold air valve upon the 125 coincidence of a predetermined amount of opening of the hot air valve and a predetermined rise of temperature of the air passing the same and opening such cold air valve more or less incident 130

to increase or decrease in the temperature
of the combined currents of air passing both
said valves, and an actuator for the out-
let valve having a lost motion connection
5 with the said hot air valve for opening the
said hot air valve upon a predetermined
amount of opening of the outlet valve and

for opening the cold air valve upon a fur-
ther predetermined amount of opening of
the said outlet valve.

In testimony whereof I have hereunto
signed my name this 21st day of December,
1916.

CARL F. SCHULZ.
